US00D421968S

United States Patent [19]

Matsumura

[11] Patent Number: Des. 421,968

[45] Date of Patent: ** Mar. 28, 2000

[54] **CONTACTOR FOR SEMICONDUCTOR IC TESTERS**

[75] Inventor: **Shigeru Matsumura**, Tokyo, Japan

[73] Assignee: **Advantest Corporation**, Japan

[**] Term: **14 Years**

[21] Appl. No.: **29/095,314**

[22] Filed: **Oct. 20, 1998**

[30] **Foreign Application Priority Data**

Apr. 21, 1998 [JP] Japan 10-11416

CLAIM

The ornamental design for a contactor for semiconductor IC testers, as shown and described.

DESCRIPTION

FIG. 1 is a perspective view of a contactor for semiconductor IC testers showing my new design;

FIG. 2 is a top plan view in a reduced scale of FIG. 1;

FIG. 3 is a bottom plan in a reduced scale of FIG. 1;

FIG. 4 is a front elevational view in a reduced scale of FIG. 1, the rear elevational view being a mirror image of the front elevational view;

FIG. 5 is a left side elevational view in a reduced scale of FIG. 1, the right side elevational view being a mirror image of the left side elevational view; and,

FIG. 6 is an enlarged center horizontal cross-sectional view of FIG. 2.
